CLEANSING AND DEODORIZING DEVICE
FOR WATER CLOSETS

Edward T. Ahern, New Haven, Conn.

Application October 7, 1939, Serial No. 298,342

3 Claims. (Cl. 4—227)

This invention relates to an improvement in a cleansing and deodorizing device for water closets, hereinafter referred to as a solution.

One object of the invention is to provide means for discharging a predetermined amount of solution of predetermined strength into the water that is to remain in the bowl of a toilet after flushing.

Another object is to provide means for discharging the solution without diluting the same in its container.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

20 Fig. 1 is a sectional view of a toilet-tank illustrating my solution-distributor;

Fig. 2 is a front view, partly in section, of the distributor on a larger scale;

Fig. 3 is a sectional view on the line 3—3 of Fig. 2;

Fig. 4 is a perspective view of the siphon-tube detached;

Fig. 5 is a perspective view of the vent-tube detached;

30 Fig. 6 is a sectional view of a toilet-tank illustrating a modified form of the distributor;

Fig. 7 is a side view partly in section of the overflow-pipe, showing the distributor located therein;

35 Fig. 8 is a vertical sectional view showing the details of construction of the distributor located in the overflow-pipe;

Fig. 9 is a sectional view on the line 9—9 of Fig. 8; and

40 Fig. 10 is a sectional view on the line 10—10 of Fig. 8.

In carrying out my invention, I employ a mixing-chamber 15 adjustably connected to the lower end 16 of a solution feed-pipe 17, the upper end 18 of which is connected to a container 19 of any desired form, herein shown as of box-like form, adapted to be suspended in the toilet-tank 20. The two parts of the feed-pipe are connected by a coupling-sleeve 21 to provide for lengthening or shortening the feed-pipe, and the lower end 16 may be held in position by a lock-nut 22. The toilet-tank is provided with the usual inlet-pipe 23, a valve 24, a float 25 to control the valve, and a seat 26 at the upper end of the flush-pipe 27 to receive

a ball-valve 28 adapted to be raised in the usual manner.

Extending into the mixing-chamber 15 and downward therefrom is a siphon-tube 29 having a discharge-end 30 of any desired diameter directed toward the flush-pipe 27 and adjustably connected to the siphon-tube by a coupling-sleeve 31, so as to shorten or lengthen the siphon-tube 29 as required. Opening out of the top of the mixing-chamber is a vent-pipe 32 which may be formed with a trap 33. Extending upward through the feed-pipe 17 is an air-pipe 34 which extends into the solution-container 19 to admit air thereto as the solution is drawn off. Preferably, the upper end 35 of the pipe 34 is flexible, so as to bend if the feed-tube is shortened.

When the mixing-chamber 15 is empty, the solution will flow down the feed-pipe 17 until the lower end of the feed-pipe is submerged and the flow stopped. Then, as water rises in the tank 20, water will pass through the siphon-tube 29 and mix with the solution, the air in the chamber escaping through the vent-pipe 32.

As the amount of solution discharged from the container can be determined, no unnecessary waste of solution can take place. The parts are so arranged that when the toilet is flushed, the solution will not be discharged until just before the ball-valve 28 closes the flush-pipe 27, so that the solution mixes with the water that is to remain in the bowl, where it will act as a cleaner, stain-preventive and deodorant.

The water in various sections of the country differs in mineral content, which is the cause of more or less staining of toilet fixtures by standing water. This device can be regulated to supply the proper amount of solution to the flushing water to prevent the staining of fixtures in any section of the country, the amounts to be determined by the mineral content of the water in that particular section and the condition of the pipes, particularly iron, through which it is supplied.

In many cases toilet tanks are regulated or adjusted to use much less water in the flushing operation than the type referred to above. Other standard makes vary in the amounts of water remaining in the bowl after flushing.

In the construction of these tanks, a small copper refill-pipe is connected with the water-supply check-valve 24, and directed into the overflow-pipe, so that after the ball-valve seats and closes the flush-pipe, and while the tank is refilling, sufficient water will be discharged
